RECLINING CHAIR

Fred J. Piotraschke, Clayton, Mo.

Application June 5, 1950, Serial No. 166,100

1 Claim. (Cl. 155—26)

1

This invention relates to a reclining chair for barber and beauty shops or the like.

An object of this invention is to provide a chair for use in barber and beauty shops which includes an extensible supporting column wherein the seat and back may be rocked downwardly and rearwardly so as to more conveniently support a person seated in the chair in a reclining position.

Another object of this invention is to provide an improved means whereby the back is swingably secured to the seat structure and the back will swing downwardly and rearwardly in proportion to the rocking of the seat structure.

With the above and other objects in view, my invention consists in the arrangement, combination and details of construction disclosed in the drawings and specification, and then more particularly pointed out in the appended claim.

In the drawings:

Figure 1 is a detailed side elevation partly broken away and in section of a chair constructed according to an embodiment of this invention.

Figure 2 is a plan view partly in section of a reclining structure.

Figure 3 is a fragmentary sectional view taken on the line 3—3 of Figure 1.

Figure 4 is a fragmentary sectional view taken on the line 4—4 of Figure 2.

Referring to the drawings, the numeral 10 designates generally a base structure formed with a hollow column 11 within which an extensible column 12 is slidably mounted. The extensible column 12 is adapted to be raised or lowered by conventional hydraulic means or the like, and the upper end of the column 12 has secured thereto an annular flange 13 and a head plate 14.

An elongated horizontally disposed plate 15 is secured to the head plate 14 and is formed at the opposite ends thereof with a pair of upstanding upwardly tapered ears 16. A seat structure generally designated as 17 is rockably mounted on the ears 16 and includes a frame 18 which is covered by a cushioned covering means 19. The frame 18 includes a pair of parallel spaced apart angle bars 20 secured in the lower portion of the frame 18, and the angle bars 20 are rockably secured to the ears 16 by means of a shaft 21 extending through the lower portions of the ears 16.

The angle bars 20 include depending angle bars 22 terminating in forwardly projecting bars 23. A foot rest 24 is secured to the lower bars 23 in forwardly offset position by means of a pair of upwardly and forwardly extending supporting bars 25. A seat back member 26 is pivotally secured to the rear ends of the bars 20 by means of a pair of downwardly extending bars 27 which are secured at their upper ends to the rear of the back 26 and extend downwardly beneath the rear of the frame 18 and terminate in upwardly projecting arms 28.

The rear ends of the bars 20 are upwardly bowed as at 29, and the extensions of the rear bars 27 are pivotally secured to the bowed exten-

sions 29 by pivot means 30. A pair of arm rests 31 are disposed above the seat 17 being mounted on upwardly extending supporting bars 32 which are pivotally secured at their lower ends to bearings 33 disposed beneath the seat 17. The upper ends of the arm rest supporting bars 32 are pivotally secured to the forward ends of the parallel sides of a U-shaped member 34 secured beneath the arm rests 31 and projecting rearwardly on the opposite sides of the back 26.

The bight 35 of the U-shaped member 34 is pivotally secured to the rear of the back 26 by bearings 37. In order to provide a means whereby the rearward and downward swinging of the back 26 will be proportioned according to the upward rocking or the tilting of the seat 17, each extension 28 is connected with an ear 16 by means of a link 38 which at its forward end is formed with a right angular extension 39 engaging through an opening 40 formed in the ear 16 above the shaft 21. The rear or lower ends of each of the links 38 are formed with right angular extensions 41 pivotally engaging through the extension 28 below the pivot 30.

In the use and operation of this chair, in the normal position of the chair, the seat and back will be disposed as shown in full lines in Figure 1. When it is desired to position the chair in a reclining position the back 26 is swung downwardly to substantially the dotted line position shown in Figure 1. At this time the seat 17 will be disposed at substantially an obtuse angle with respect to the back 26, and the arm rests 31 will also be disposed at an obtuse angle to the back 26. It will be understood that any suitable means may be provided for locking the chair in either an upright position or in a selected reclining position.

What is claimed is:

In a device of the character described, a base, a column slidably disposed for vertical movement in said base, a head plate on said column, upstanding ears on said plate, a seat frame including a pair of spaced angle bars, means pivotally securing said bars to intermediate portions of said ears, upturned ends on said angle bars extending interiorly of said frame, a seat back including a pair of downwardly extending bars, reverted end portions on said last named bars extending interiorly of said seat frame, a pivotal connection between the reverted ends of said last named bars and the upturned end of said first named bars, and a link connecting the top portion of each of said ears to a reverted end portion of one of said last named bars.

FRED J. PIOTRASCHKE.
